John D. Buzzeca,
Letters Patent.

(Patented June 2, 1836.)

The schedule referred to in these Letters Patent, and making part of the same, containing a description in the words of the said John D. Buzzeca himself of his improvement in the machine for cutting and dressing granite, marble or other stone.

This machine consists of a movable frame standing upon upright posts. Inside of the sides & rails or beams of the frame are grooves in which the carriage containing the machine is to move forward and backward on friction wheels. So the moveable carriage is on or more metallic cylinders or discs arranged which are set spirally upon or more rows of metallic cylinders, or sockets in which the carriage is confined; or are to be connected. The discs are to be of various sizes & forms for the purpose of dressing, moulding, grooving and polishing granite, marble and stone of all descriptions. The cylinders or cylinders are to revolve principally by means of a chain band passing around two wheels over which is at each extremity of one of the side rails or beams above mentioned. Between said extremities and wheels, is a wheel connected to each cylinder or by bands (when more than one is used) and over which last named wheel or wheels said band passes, communicating the motion and power of the first named wheel to the latter and by which motion the wheel or wheels connected to the axle or axles of the cylinders or by cylinders by means of a gear box in one end of the former, and a gear train and one end of the latter. The cylinders or cylinders are made to revolve.

The train is bound down upon the intermediate wheels above mentioned by means of friction collars bearing upon the band. The wheels are arranged over which the chain band passes or over which band is to the side of the chain. The axle of one of the wheels at the end of the carriage passes through two metallic blocks these blocks are work through two cylinders connected to the carriage, so that the blocks can be moved backward and forward.

forward by the desire passing through a metalic nut confined with
pinions of the machine. At the end of each desire is a round tangent which
is inverted and so fastened into the end of each block (through which
the axle of the wheel passes) as to revolve in such a manner that when
the desires are turned, the blocks move horizontally backward or
forward through the boxes; whereby the chain band may be tightened
or relaxed at pleasure. The motion of the moveable carriage forward
is accurately gauged and regulated either by a combination of two
meshing into each other operated upon by a small wheel on the axle
of the cylinder wheel, and by one of the wheels thus combined as
meshing into and acting upon the cog rail confined to the side of the
side beam or rail of the frame; the last named wheel can be
geared or ungeared at pleasure by means of a lever operating upon the
top supporting one end of said wheel. The carriage is brought by
a wheel meshing into a wheel on the axle of the cylinder wheel
and at the same time meshing into the cog wheel, and the carriage
meshing into the cog rail before mentioned, which wheel can be
geared or ungaed at pleasure by means of a lever; or the car-
riage is to be moved forward by means of a screw situated
near and inside of the carriage running parallel with the cog rail
upon the beam or side rail of the carriage. The screw is connected at
one end to the beam or side rail of the carriage, and is fastened
securely, and caused to revolve by means of a wheel on one end
of the desire which wheel meshes into a wheel on the axle of any
wheel which carries the base situated at one end of the frame so
that by the revolution of the desire, the screw operating upon a metalic
block which is connected by bars or slides to one end of the moveable
carriage and the other end of the block resting upon the screw. The
end of the block which rests upon the screw is of a conical or taper form
and is ungaed and formed as to mesh into the threads of the screw
and thereby the revolution of the desire the carriage is moved forward.
The above named block can be geared or ungaed by means of
lever. The carriage in this case is moved backward in the same
manner.

united, as is moved backward, when moved forward by a combination of wheels. Between the rails of the frame is a bed or platform to hold the stone or any other article to be operated upon, over which the moveable carriage is to pass. This platform is made of timber with soft bars forming gentle work over laid with metallic plate and is supported by upright posts with round heads at each end. The upper ends are connected by sockets to the timbers of the platform, and the lower ends resting in sockets confined to the two screw bars situated below the platform and extending outside the frame of the carriage. The platform is moved up and down by means of screws working through nuts connected to the heads of the transverse bars, which screws screw on their outer ends requiring. The screw strands perpendicular. The lower ends resting in metallic sockets passing through the nuts described above, and the upper ends are supported by boxes inserted in or connected to posts, which posts are connected to the beams of the frame ^{and} project outside of the machine, these boxes are turned by levers by which the platform is raised or lowered as occasion demands.

What I claim as new and for which I ask letters patent is the particular arrangement and combination of the cutting and polishing cylinders and rollers, the method of raising and lowering the stone, and the arrangement of machinery for raising the carriage and revolving the cylinders or cylinders.
